REFRIGERATOR CONSTRUCTION

William Herbert Ellis, Newburgh, Ind., assignor
to Servel, Inc., New York, N. Y., a corporation
of Delaware

Application December 2, 1933, Serial No. 700,675

4 Claims. (Cl. 220—9)

This invention relates to refrigerator construction, and more particularly to cabinet wall construction and the provision of a wall having improved heat insulating qualities.

5 In the manufacture of refrigerator cabinets of the household type it is customary to wrap individual slabs of insulating material in waterproof paper or the like, after which the individual slabs are placed in position between the liner of the 10 refrigerator and the outer casing, in order to prevent heat flow from the exterior into the interior of the cabinet. With this construction crevices are left between the individually wrapped slabs through which crevices a breathing action 15 may occur between the outside air and a layer of air surrounding the liner, which therefore greatly reduces the efficiency of the insulation.

It is an object of the invention to overcome the aforementioned obstacles and provide an insulation in which slab insulation can be used with 20 crevices between the joints eliminated, and at the same time, the cost of production materially reduced by elimination of labor in separately wrapping the slabs of insulating material.

25 This invention consists essentially in covering the liner of the cabinet with a paper envelope shaped to fit the liner, then applying the slabs of insulation and suitably fastening such slabs in place, after which an outer enclosing envelope 30 of paper or the like is applied and the adjoining edges of the inner and outer envelopes are sealed together.

Other objects and advantages will be apparent 35 from the following description taken in connection with the accompanying drawing, wherein

Fig. 1 is a vertical section through a refrigerator cabinet illustrating one application of the invention;

Fig. 2, a horizontal section on the line 2—2 of 40 Fig. 1;

Fig. 3, a fragmentary section on line 3—3 of Fig. 1; and

Figs. 4 and 5, fragmentary details.

Referring to the drawing, a refrigerator cabinet is formed of an outer casing or shell 10 and an inner casing or liner 11, between which are disposed slabs of insulation 12. The slabs 12 are used on account of convenience in handling and it is customary to wrap the slabs in waterproofed paper or the like to prevent breathing or air circulation, and consequent heat conduction through the slabs.

The cabinet is provided with a front frame 13 to which both the outer casing 10 and the liner 11 are attached. In order to simplify the con-

struction, reduce the labor cost, and increase the insulating value, the slabs 12 about the liner 11 all in accordance with the present invention are encased in a single wrapping or sheeting. This sheeting comprises an inner envelope 14 and an outer envelope 15, both of which are of waterproof construction, and through which air cannot pass.

In assembling, the inner envelope is first placed in position about the liner, and thereafter the 10 insulating slabs are all placed in position in a manner to snugly enclose the liner except at the front and at the liner opening 16 in the rear wall of the liner. The insulation and inner envelope are secured in place and tightly in engagement 15 with the liner by means of straps or bands of metal 17 and 18, the bands 17 being vertically applied and the straps 18 being horizontally applied, and serving to bind the assembly to the front frame, the straps 17 merely serving to bind 20 the insulation and inner envelope to the liner. This construction of securing the insulation to the liner is similar to that shown in Patent No. 1,878,111 granted Sept. 20, 1932, to W. D. Collins.

While the use of bands 17 and 18 of metal or 25 the like has been described for securing the insulation in position, the invention is not so limited and contemplates the use of any desired fastening means for accomplishing the same or equivalent result.

30 About the slabs of insulation held by the straps 17 and 18 to the liner, is placed an outer envelope of paper or other material preferably treated to render the same impervious to the passage of both air and water. The inner envelope has its front 35 marginal portion turned outwardly so that it is in contact at its edge with the outer envelope, and these contacting edges are fastened together by cementing or the like to form an annular, tight joint between the inner and outer coverings for 40 the insulation.

In the type of cabinet illustrated the cooling unit is removably inserted through the rear of the liner into the compartment to be cooled within the interior of the liner. It is therefore necessary to seal the inner and outer envelopes around this opening, and in order to accomplish this result, these envelopes are slit in a manner shown in Figs. 4 and 5, the envelope of Fig. 4 being provided with a vertical central slit 19 and at the 45 extremities of the vertical slit with two horizontal slits 20. The other envelope is reversely slit, that is, with a horizontal central slit 21 and with vertical slits 22 at the ends of the horizontal slit. The thus formed flaps are then folded along the 50

dotted lines indicated in these figures, and such four flaps formed in the two envelopes bridge the space between the envelopes at the sides, top and bottom of the opening through which the 5 cooling unit is applied. Angle strips 23 (see Fig. 3) are applied at the corners to seal the joint between the two envelopes. The flaps of the envelopes may be cemented to the cooperating envelope. This construction provides an air-tight container in which is disposed the entire 10 insulating assembly with the exception of the closures for the front and rear openings of the cabinet, and the breathing or passage of air through the cabinet wall can only occur around such 15 openings.

It will be apparent to those skilled in the art that various other changes may be made in the construction and arrangement without departing from the spirit of the invention, and therefore 20 the invention is not limited to that which is described in the specification and shown in the drawing, but only as indicated in the appended claims.

What is claimed is:

- 25 1. Refrigerator cabinet construction comprising an inner casing, insulation about said inner casing, said inner casing and insulation being provided with an opening affording a passage into the inner casing, a sealed envelope enclosing 30 said insulation and slit longitudinally and transversely of said opening and forming flaps, said flaps being projected through the opening in said insulation to the opposite side of the same to line said opening and being sealed about the opening.
- 35 2. A refrigerator cabinet comprising a front supporting frame, an inner liner defining a food compartment secured to said frame, an outer shell forming a casing for said liner and spaced from the latter to provide an insulating space therebetween, an inner envelope substantially 40 completely encasing the liner, individual slabs of insulation disposed substantially throughout said

insulation space, an outer envelope overlying said slabs and connected in substantially air-tight relation to the inner envelope and together with the latter completely encasing said slabs, said envelopes being comprised of relatively thin 5 flexible material of low heat conductivity.

3. A refrigerator cabinet comprising a front supporting frame, an inner liner defining a food compartment secured to said frame, an outer shell forming a casing for said liner and spaced 10 from the latter to provide an insulating space therebetween, an inner envelope substantially completely encasing the liner, individual slabs of insulation disposed substantially throughout said insulation space, an outer envelope overlying 15 said slabs and having its free edges connected in substantially air-tight relation to the free edges of the inner envelope and together with the latter completely encasing said slabs and covering the joints therebetween to prevent 20 breathing or passage of air transversely of the insulation, said envelopes being comprised of relatively thin flexible material of low heat conductivity such as waterproofed paper or the like.

4. A refrigerator cabinet comprising a front 25 supporting frame, an inner liner defining a food compartment secured to said frame, an outer shell forming a casing for said liner and spaced from the latter to provide an insulating space therebetween, an inner envelope substantially 30 completely encasing the liner, individual slabs of insulation disposed substantially throughout said insulation space, means holding the insulation slabs in place and the liner and frame together, and an outer envelope overlying said slabs 35 and holding means, said envelopes being comprised of relatively thin flexible water-proof material of low heat conductivity and having their marginal edge portions joined in air-tight relation at the front of the cabinet. 40
